CLAIM

The ornamental design for an applicator unit for a skin care composition, as shown and described.

DESCRIPTION

FIG. 1 is an upper perspective view of the applicator unit for a skin care composition showing my design;

FIG. 2 is a side elevation view thereof, an opposite side elevation view being a mirror image thereof;

FIG. 3 is a rear elevation view thereof;

FIG. 4 is a front elevation view thereof;

FIG. 5 is a top plan view thereof; and,

FIG. 6 is a bottom plan view thereof.

The broken line showing of parts of the drawings is included for the purpose of illustrating use and environment and forms no part of the claimed design.

1 Claim, 3 Drawing Sheets
